Primary Examiner — Brett Miller*Assistant Examiner* — Rani J Abdallah(74) *Attorney, Agent, or Firm* — QuickPatents, LLC; Kevin Prince(57) **CLAIM**

The ornamental design for a dispensing bottle, as shown and described.

DESCRIPTION

FIG. 1 is a perspective view of a dispensing bottle, showing my new design;

FIG. 2 is a front elevational view thereof;

FIG. 3 is a rear elevational view thereof;

FIG. 4 is a left-side elevational view thereof, the right-side elevational view being a mirror image thereof;

FIG. 5 is a top plan view thereof;

FIG. 6 is a bottom plan view thereof; and,

FIG. 7 is an exploded perspective view thereof.

The broken lines on FIG. 6 depicting a battery compartment for an illumination source form no part of the claimed design.

1 Claim, 6 Drawing Sheets(56)
